UNITED STATES PATENT OFFICE.

SAMUEL SPARLING, OF NEW YORK, ASSIGNOR TO HIMSELF, AND LAWRENCE A. BOLAND, OF BROOKLYN, NEW YORK.

TOY CANNON.

SPECIFICATION forming part of Letters Patent No. 535,124, dated March 5, 1895.

Application filed April 17, 1894. Renewed January 19, 1895. Serial No. 535,565. (No model.)

To all whom it may concern.

Be it known that I, SAMUEL SPARLING, a citizen of the United States, residing in the city and county of New York, in the State of New York, have invented a certain new and useful Improvement in Toy Cannons, of which the following is a specification.

The invention is intended to supply an absolutely safe toy for children, giving a great number of detonations at small expense. It tends to develop the mechanical talents of the children.

The toy uses ammunition in the form of flexible strips. The slight explosions resulting from the several discharges induce a smart report and send a small quantity of smoke out through the bore of the cannon at each discharge. The manipulation is simple.

The accompanying drawings form a part of this specification and represent what I consider the best means of carrying out the invention.

Figure 1 is a side elevation with a portion shown only in dotted lines. Fig. 2 is a central longitudinal vertical section, showing the toy complete, and Fig. 3 a plan view. Fig. 4 is a rear elevation of a portion on a larger scale.

Similar letters of reference indicate corresponding parts in all the figures where they appear.

A is a casting of brass or other suitable material, preferably nickelized and polished. Its form imitates a late and attractive style of cannon; but instead of being mounted on trunions, it is equipped with a stout foot A'. This is secured on a block of wood B by means of a wood-screw. It is bored in the ordinary manner of a cannon, as indicated by a, and is mortised, as indicated by a', in the thick portion near the breech.

D is a cylinder inserted partially into the mortise a', and firmly set on an axis E, provided with a crank-handle E', and supported in bearings A², A². The periphery of the cylinder is smoothly finished except for equally spaced projections D'. The faces of the cylinder are smoothly finished, except that one face is provided with equally spaced projections D².

The ammunition is a specially adapted strip

of paper, with small wafers of fulminate carried around on the periphery of the cylinder, kept in register by the engagement of the projections D' in holes in the strip.

G is a lever or hammer turning on a removable pin F, and adapted to serve as a hammer, one arm carrying a head G', adapted to strike on the periphery of the cylinder nearly fair, but with a slight swell and inclination of the face to throw the exploding gas downward, for a purpose which will presently appear. The other arm, G², is arranged to receive motion from the several projections D². The hammer is subject to the force of a spring H, secured to the body of the cannon at H', and acting on the hammer to throw its head G' always into smart contact with the cylinder.

I is a hood or shield turning on a center I' carried on the body of the cannon, and matching loosely over the parts where the explosion is produced. This can be thrown backward to allow the parts to be seen in operation, and the device can be operated and the cannon fired any number of times with the hood thus open; but the enjoyment of the toy is increased by operating with the hood in place, because it tends still further to retain the slight smoke produced by the explosion and direct it outward through the bore of the cannon. The slight bevel on the face of the hammer throwing the force of the explosion downward directs the smoke into the bottom of the mortise, from which it has an easy escape through the open bore a. The hood I, by partially inclosing the cylinder and its adjuncts, increases the certainty that the small quantity of smoke produced shall be thus retained and discharged.

J is a scraper fixed on the cannon immediately in front of the cylinder, and presenting two branches J', J², one on each side of the line of projections D'. This scraper bears gently on the periphery of the cylinder and aids to insure that the material remaining from the explosion is removed. Such material will usually be in the form of partially burned paper, retaining so much strength that the thorough cleaning of the cylinder on each side of the projections D' will also remove the material extending across, and thus cleaning the spaces in the line of the projections.

The ribbon or strip of paper M is wound on a spool K set on a pin L, supported between vertical arms A³, A⁴. A slight dishing spring N is inserted at one end or at each end of the spool to insure a gentle friction. The strip M is led from this spool under a horizontal transverse guide-pin P, and thence up through the mortise a' and engaged on the projections D'.

I attach importance to the form of the parts as facilitating the insertion of the paper. The back face of the post or foot A' is curved and smoothly finished, as indicated at a². The front end of the strip of paper led from the spool K under the guide-pin P is deflected upward by the curved face a². A slit a³ above, receives the end thus deflected and directs it upward so that it is easy to find its upper end and engage it on the projections D'.

The strip M carries equally spaced wafers of fulminate, between which are holes m adapted to receive the projections D'.

The parts may be made by machinery. They should be finished and put together with sufficient nicety to work with ease, but there is no necessity for the extreme accuracy employed in arms which are intended for use with powder.

Modifications may be made without departing from the principle or sacrificing the advantages of the invention.

The projections D', D², may be made by drilling holes in the cylinder and inserting tightly fitting pins, but I propose in manufacturing in the large way to produce the cylinder with these projections integral, employing proper tools to finish them smoothly and reliably.

I² is a forked spring attached on the inside of the hood I, near the front, and arranged to press gently on the outer face of whatever remains of the strip of paper M on each side of the row of pins D', when it passes that point. It tends to maintain a reliable contact of the strip M with the cylinder until it reaches the scraper J.

I claim as my invention—

1. In a toy, a combination comprising the barrel A, with a foot A', presenting the appearance of a cannon, cylinder D, having projections D² on one face and also projections D' on its periphery, adapted to engage with a perforated ribbon, with means E, E', for revolving it, and the hammer G having arms G', G², and actuating spring H, arranged for joint operation as herein specified.

2. In a toy a combination comprising the barrel A, with a foot A', cylinder D, having projections D' on its periphery and projections D² on one face, with means E, E' for revolving it, and the hammer G having arms G', G², actuating spring H, removable pin L, guide P, spool supporter A³, A⁴, spool K, friction spring N, curved surface a², and slot a³,

arranged for joint operation substantially as herein specified.

3. In a toy, a combination comprising the barrel A with a foot A', cylinder D, having projections D' on its periphery and projections D² on one face, with means E, E', for revolving it, and the hammer G having arms G', G² actuating spring H, removable pin L, guide P, spool supporter A³, A⁴, spool K, friction spring N, curved surface a², and slot a³, and scraper or cleaner J, J', J², arranged for joint operation substantially as herein specified.

4. In a toy, a combination comprising the barrel A with a foot A', cylinder D, having projections D' on its periphery, and projections D² on one face, with means E, E', for revolving it, and the hammer G, having arms G', G² and actuating spring H, with the striking face G' swelled and slightly inclined relatively to the adjacent surface of the cylinder adapted to throw the force of each explosion downward, all substantially as herein specified.

5. In a toy, a combination comprising the barrel A, with a foot A', cylinder D, having projections D' on its periphery and projections D² on one face, with means E, E' for revolving it, and the hammer G, having arms G', G², and actuating spring H, with the hammer face G' swelled and slightly inclined relatively to the adjacent surface of the cylinder, adapted to throw the force of each slight explosion downward, and the hood I turning on the center I', adapted to cover the parts where the explosion is produced, all arranged for joint operation substantially as herein specified.

6. In a toy a combination comprising the barrel A having the bore a and a mortise a' communicating with the bore, the cylinder D having projections D' on its periphery and also projections D² on one face, with means E, E' for revolving such cylinder, and the hammer G having arms G', G² and actuating spring H with the arm G', having its striking face slightly inclined relatively to the adjacent surface of the cylinder, adapted to throw the force of each slight explosion downward through the mortise and outward through the bore, and with the hood I adapted to cover the parts where the explosion is produced, and the forked spring I² carried on said hood adapted to press gently on the débris of the strip M, the whole being arranged for joint operation substantially as herein specified.

In testimony that I claim the invention above set forth I affix my signature in presence of two witnesses.

SAMUEL SPARLING.
